UNITED STATES PATENT OFFICE.

HENRY N. MÜLLER, OF PITTSBURGH, PENNSYLVANIA, ASSIGNOR TO THE JOHNS-PRATT COMPANY, OF HARTFORD, CONNECTICUT, A CORPORATION OF CONNECTICUT.

FUSE-CLIP.

1,133,569.

Specification of Letters Patent. Patented Mar. 30, 1915.

Application filed July 15, 1914. Serial No. 851,091.

To all whom it may concern:

Be it known that I, HENRY N. MÜLLER, a citizen of the United States, residing at Pittsburgh, in the county of Allegheny and State of Pennsylvania, have invented a new and useful Improvement in Fuse-Clips, of which the following is a specification.

This invention relates to the construction of those fuse clips which are provided for receiving the terminals of inclosed fuses of the knife blade contact type and particularly such fuses as are designed to carry relatively large currents although, of course, these clips may be used for receiving the terminals of fuses of small capacity.

Fuses, especially those of large capacity, require a proper area of contact between the surfaces of their terminals and the surfaces of the clips with which they are connected, and these clips are usually made in the form of spring fingers in order that the fuses may be quickly placed in or removed from the circuit. Such spring fingers must press tightly against the fuse terminals over a considerable area otherwise the flow of current between the clips and the fuse terminals causes heating which heating not only materially affects the carrying capacity of the fuse but also tends to soften and destroy the elasticity of the clip fingers. If the elasticity is destroyed the clips are liable to become more or less bent and stay bent when a fuse is inserted or removed and this increases the objectionable factor of improper contact and consequent heating.

The object of this invention is to construct a simple and cheap terminal clip which has great flexibility, and the contact surfaces of which are self alining and the spring portions are so distant from the contact surfaces that they will not become heated and lose their elasticity.

Figure 1 of the accompanying drawings shows a plan of a fuse block with a pair of fuse clips which embody the invention. Fig. 2 shows a side view of the same. Fig. 3 shows a section on plane indicated by dotted line 3—3 on Fig. 1. Fig. 4 shows a section on plane indicated by dotted line 4—4 on Fig. 1.

The clip illustrated has a base 1 which is desirably a brass casting that at one end has a wire terminal clamp 2 and at the other end has four upwardly extending posts 3.

The contact plates 4 are mounted oppo-

sitely to each other between the posts. Each of the plates shown is fastened to the inner end of a stud 5 that has its outer end held by the upper end of an upwardly extending spring plate 6. The studs pass between and are loosely retained in position by the posts, and the spring plates are fastened to the base of the clip by the screw 7 and nut 8. Current is conveyed to the contact plates by a plural number of thin sheet metal leaves 9, the upper ends of which are held between the studs and the backs of the contact plates while the lower ends are clamped between the lower ends of the spring plates and the base of the clip. The 70 clips are mounted on an ordinary insulating block 10.

With this construction the contact plates are free to aline themselves with and fit flatly against the side of the fuse terminals that are forced between them. The spring plates, which may be desirably made of high tempered steel, that support the contact plates press the contact plates firmly together without limiting the self alinement 75 of the contact plates, and the spring plates are so far from the contact plates that they are not liable to become heated and lose their elasticity even should the contact plates fail to make close contact with the 80 fuse terminals. Current is chiefly conducted to the contact plates by the conducting leaves which are made sufficiently large to carry the requisite amount of current and yet are so thin that they do not offer any 85 material resistance to the self alinement of the contact plates when fuse terminals are forced between them.

The invention claimed is:

1. A fuse clip having a conducting base, 95 spring plates with their lower ends fastened to the base, a pair of contact plates, conducting studs extending from the middle of the backs of the contact plates at right angles thereto to the upper ends of the spring 100 plates, and means projecting from the base for loosely retaining said studs.

2. A fuse clip having a conducting base, spring plates fastened to and extending upwardly from the base, a pair of contact plates, means extending from the middle of the backs of the contact plates to the upper ends of the spring plates, and conducting means connecting the contact plates with the base.

3. A fuse clip having a conducting base, spring plates extending upwardly from the base, a pair of contact plates, studs connecting the contact plates with the upper ends 5 of the spring plates, and conducting leaves connecting the contact plates with the base.
4. A fuse clip having a conducting base, spring plates with their lower ends clamped to the base, a pair of contact plates, studs 10 connected at their inner ends with the center of the contact plates and at their outer ends with spring plates, and conducting leaves extending from the middle of the contact plates to the base.
- 15 5. A fuse clip having a conducting base, spring plates with their lower ends clamped to the base, contact plates, studs connecting the contact plates with the upper ends of

the spring plates, and conducting leaves with their upper ends held between the 20 studs and the contact plates, and their lower ends fastened between the base and the lower ends of the spring plates.

6. A fuse clip having a conducting base with a wire terminal clamp and upright 25 posts, conducting studs loosely retained by said posts, spring plates with their lower ends fastened to the base and their upper ends engaging the outer ends of the studs, contact plates attached to the inner ends of 30 the studs, and conductors extending from the contact plates to the base.

HENRY N. MÜLLER.
